CENTRIFUGALLY OPERATED SWITCH

Gilbert James Butterworth, Chester, Pa., assignor
to Sperry-Sun Well Surveying Company, Philadelphia, Pa., a corporation of Delaware

Application May 4, 1949, Serial No. 91,349

16 Claims. (Cl. 171—97)

1

This invention relates to bore hole measuring and more particularly to a centrifugally operated control switch capable of providing repeated closing of an electric circuit such as may be used in connection with the various instruments commonly employed in bore hole measuring apparatus.

In the art of bore hole measuring it is customary to go-devil instruments down into a drill stem and by raising the drill stem and repeatedly operating the instruments at various levels within the bore hole secure a series of records of conditions existing within the bore hole correlated with the depths at which the various records were made.

It is common practice to record indications of bore hole inclination, temperature and other characteristics by photographic or other means which are generally electrically controlled. Heretofore one of the problems associated with the procurement of such a record has been that of providing suitable switching means controllable from the surface of the ground for terminating the operation of the recording element or repeatedly initiating the sequence of recording operations at various depth levels. Such a switch means must not be responsive to vibration, inclination, or impact occurring during the normal passage of the instruments down through the drill stem.

One device desirably used with such a switching means is that described in the patent to Roland Ring, No. 2,246,319, dated June 17, 1941, and also illustrated in the patents to Smith No. 2,301,757, dated November 10, 1942, Kothny No. 2,317,386, dated April 27, 1943, Emerson et al. No. 2,412,976, dated December 24, 1946, Kothny 2,415,249, dated February 4, 1947, and Kothny No. 2,424,358, dated July 22, 1947. The Ring instrument is characterized by a slow continuous marking action, specifically electrolytic in character, whereby a record of the position of the instrument within a bore hole is made only when the instrument remains stationary for an extended period of time. For a better understanding of the nature of the present invention, which is not, however, limited for its application to said instrument of the above mentioned patents, the operation of said instrument may be described as follows:

If the instrument is run into a bore hole, either within a drill stem or in an open hole, by means of a wire line or cable, the movements of the instrument incidental to its descent into the hole cause a pendulum to move about relative to a

record member, so that even though current is continuously flowing from the pendulum to the record member, no point of the record member is exposed to the current action for a sufficiently long time to receive a definite marking. When the instrument reaches the level at which a record of inclination is to be made, it is brought to rest and held in such position for a period upwards of about one minute, with the result that the electrolytic action is concentrated at one point of the record member and an easily distinguishable spot is made thereon. If it is then desired to make one or more additional records at other levels, the instrument is moved to these successive levels and permitted to remain at them for different periods of time, with the result that marks differing in intensity and/or size are produced which, by their nature, can be identified with the particular levels through a knowledge of the relative times during which the instrument was stationary. Following the completion of the record or records, the instrument is then withdrawn continuously from the hole and in this withdrawing movement, as well as in the periods of movement between the successive recordings, the pendulum will swing relative to the record member so that again no obliterating markings are produced.

In the case of operation of the above type, the instrument is perfectly satisfactory and requires no timing means whatever. However, a common practice in the making of records with surveying instruments involves their being dropped freely through a drill stem so that they come to rest in a position adjacent the bit. During this location in a position of rest, a record is made under the control of suitable timing means, and the instrument is then recovered when the bit is brought to the surface. Generally speaking, such go-devil records are made at a time when it is necessary to bring the bit to the surface to check the progress of the drill.

In the use of said Ring instrument in go-devil fashion, the motion of the instrument through the drill stem prevents the making of any record during its fall, and a record is then made by holding the drill stem stationary for a sufficient period of time while the instrument rests adjacent the bit. If the drill stem was then raised and dismantled by continuous work of the drilling crew, the instrument would be subject to sufficiently continuous agitation, with only quite limited periods of rest, so that no record obliterating markings would be produced on the record member. However, it is not usual for a derrick

crew to work continuously in removing a drill stem from deep holes, and generally speaking, even if some mechanical reason for delay does not occur, the workmen, after raising the drill stem part way, will take a short period of rest before proceeding further. If an instrument of the Ring type is in the drill stem during such a period of rest, or any other period of stationary condition of the drill stem, it will be obvious that another record will be made which might be indistinguishable from the desired record unless a substantially different time of rest is involved, and even then in some rare instances, particularly where the hole is substantially straight, the two records may overlap so that the significance of the original one is lost. It is generally not desirable to rotate the drill stem during such a period of interruption of its withdrawal, and consequently, such rotation is not a practical solution to the problem.

In order to avoid the difficulties described in go-devil operations, the Ring instrument has been provided with various circuit interrupting devices as disclosed in said Smith, Emerson et al. and Kothny patents.

The present invention relates to the provision of means for terminating the recording action at a desired time, being particularly useful for termination of the recording action following the completion of a single record or a series of records. This means constitutes, in one aspect, an improvement over the current interrupting means of the patents referred to above.

As an example of the type of instruments which may have their operation repeatedly initiated attention is directed to the patent to Williston et al. No. 1,960,038, dated May 22, 1934, disclosing a device constituting means for obtaining a substantially continuous record of the deviation of a bore hole throughout its length and including means for automatically photographing simultaneously the position of a gyroscope, a bubble, and a time piece, from which the deviation of a hole may be readily determined at various points along its length. The switching apparatus of the present invention may be employed to enable the drill crew to repeatedly initiate the operation of an instrument such as disclosed by said Williston et al. patent and thereby reduce the loss of film resulting from the great number of pictures needlessly taken by that instrument while the instrument is being moved from one position to another within the bore hole.

The present switching means and a film moving means such as is disclosed by the Williston et al. patent may be employed in connection with instruments such as are disclosed in the patents to Hewitt No. 2,116,350, dated May 3, 1938, Hewitt et al. No. 2,169,342, dated August 15, 1939, and in the application of Einar T. Young, Serial No. 757,790, filed June 28, 1947. These disclosures show single shot photographic type instruments for recording bore hole survey information. In each instance by the addition of a film moving means controllable by the present switching means these instruments may be modified into multiple shot instruments capable of repeated operation initiated by the drill crew at the surface of the earth.

It will be evident as the description proceeds that the centrifugally operated switches in accordance with the present invention may be used for many other control purposes as, for example,

for the control of electrical, acoustic, radioactive or other logging apparatus or the like.

One of the most desirable methods for controlling operations such as reviewed above is by a centrifugally operated switching means responsive to rotation of the drill stem. However, when the drill bit is raised from the bottom of the drill hole and the drill stem is rotated at any appreciable speed, because of the great length of the free hanging drill stem there is a tendency for the drill stem to whip with a very great possibility of damage or breaking resulting.

It is an object of this invention to provide a switch which will make contact at relatively low speeds of rotation of the drill stem.

It is another object of this invention to provide a centrifugal switch which will not make contact as a result of vibration, impact, or inclination such as would result from general handling or passage of the switch within the bore hole, but which will establish an electrical contact when rotated above a predetermined speed.

These and other objects of the invention relating particularly to details of construction and operation will become apparent from the following description, read in conjunction with the accompanying drawings, in which:

Figure 1 is an elevation of the switch assembly partially in section showing floating pendulums in an outward position such as would result from rotation of the switch assembly;

Figure 2 is a transverse section taken on the plane 2-2 indicated in Figure 1 and showing in particular the pendulum sockets;

Figure 3 is a section taken on the plane 3-3 indicated in Figure 1 showing the pendulums and the electrical contacts closed thereby, this figure diagramming the electrical connections;

Figure 4 is a diagrammatic representation of an electrical circuit employed when utilizing the present invention to terminate a recording operation;

Figure 5 is a diagrammatic representation of a device employing the present invention to repeatedly initiate recording operations;

Figure 6 is a development of the surface of the timing drum associated with the device shown in Figure 5;

Figure 7 is a fragmentary elevation partly in section showing a modification of the switch assembly;

Figure 8 is a transverse section taken on the plane 8-8 indicated in Figure 7 showing the pendulums and the electrical contacts opened thereby, this figure diagramming the electrical connections; and

Figure 9 is a diagrammatic representation of an electrical circuit employed when utilizing the modification of the invention shown in Figures 7 and 8 to terminate a recording operation.

The centrifugally operated control switch comprises a sleeve 4 made of a suitable plastic or other electrical non-conductive material containing a fluid 6 which is preferably a good grade of oil, such as a transformer oil, having high dielectric properties and resistance to oxidation. In this fluid are floated pendulums 7. The pendulums are desirably formed of aluminum or other light metal tubing sealed at the upper ends by caps including pointed projecting stems 8 and at the lower ends by silver coated contact caps 18.

The pendulum stems 8 seat by floating in sockets 9 of screws 10 which are screwed into tapped bores 12 of a non-conductive member 14. The

member 14 is screwed into position in the upper end of the sleeve 4 and the sleeve is sealed by plug member 16 which is screwed into the sleeve and cemented to prevent oil leakage. The member 16 bears against the member 14 thereby locking the member 14 rigidly in position.

The lower end of the sleeve 4 is plugged by insulating member 22 which is screwed into place and cemented to prevent oil leakage. In member 22 are mounted contact bars 20 positioned so as to be contacted by lower ends 18 of the pendulums when the pendulums are in outward position. Member 22 also contains slots 19 serving to retain and guide the free ends of the pendulums to insure proper contacting with contact member 20. The pin 17, mounted in and extending above member 22 at the junction of the slots 19, is provided to prevent the pendulums from falling out of their respective slots when the instrument is inclined.

When the control switch is at rest in a vertical position the pendulums will, by virtue of their weighted lower ends 18, float in vertical positions, grouped together in the center of the liquid chamber and assume positions under the socket screws 19. When the switch is rotated at a sufficient speed the lower ends of the pendulums will move outward in response to centrifugal force and establish contacts between each of the pairs of contact bars 20 thus completing the circuit from the lead wire 24 through jumper wires 25 and 26, connecting the lower ends of bars 20, to lead wire 27. These contacts will be firm and positive contacts by virtue of the centrifugal force acting on the pendulums.

It is obvious that inclining the switching assembly or submitting the switch to horizontal impact can not possibly cause all three of the pendulums to be in outward positions simultaneously. Thus, only by rotating the assembly can a continuous circuit be established between the lead wires. The switch, therefore, can be utilized to establish contact in response to rotation of the drill stem at a speed above the predetermined value and will not establish contact as a result of inclination, impact or vibration as would occur during the lowering of the switch in a drill stem.

Inasmuch as the angle assumed by each of the pendulums is dependent upon the speed of rotation of the switch assembly the value of speed at which switch contact is established, other factors being equal, is dependent upon the length of the pendulums. Thus, reducing the length of the pendulums will cause contact to occur at higher speeds and increasing the length of the pendulums will cause contact to occur at lower speeds. Heretofore in bore hole logging the problem has been to provide reliable contact making means which would operate at sufficiently low speeds of rotation. The present invention will provide desirably reliable contact at speeds below 50 R. P. M. and, by varying the length of the pendulums, contact can be made to reliably occur at various reasonably selected and predetermined values of speed.

The viscosity of the oil in which the pendulums are floated will affect the rate at which the pendulums will move outward, in response to the centrifugal force resulting from rotation, and the rate at which they will move inward, due to the action of gravity alone when the switch is at rest. This rate of motion of the pendulums can be altered by changing the viscosity of the oil to produce characteristics of operation gen-

erally desirable for any specific operating conditions.

Figure 4 shows the present invention employed in connection with the Ring type instrument which has been hereinbefore discussed.

There is generally shown at 40 the contact elements of the present invention with lead wire 24 connected to ground. The lead wire 27 is connected through battery 42 and conductor 44 to solenoid coil 48 and through lead wire 50 to the common ground line 52. When this instrument is go-deviled into a drill stem and comes to rest at the bottom thereof current passes from the battery 54 through the current limiting resistor 56, the pendulum member 60, the contact point 62, and electrochemical record member 64 to the common ground 52 and returns to the battery through switch lead wire 66, switch contact lever 67, switch contact point 68 and lead wire 70. It will be noted that the switch contact lever 67 is held firmly against contact point 68 by the action of latch member 72 and spring 74.

If the instrument is at rest in one position for sufficient length of time electrochemical action 25 will cause an indication to be made on recording member 64 under the contact point 62. After the drill stem has been successively raised and held at rest at the various levels at which records are desirably obtained, the drill stem is then 30 rotated at sufficient speed to cause the centrifugal contact switch 40 to close completing the circuit through the switch 40, the wire 27, battery 42, the wire 44, the solenoid coil 48, the wire 50 and ground 52 thereby energizing the solenoid coil 48 and drawing the contact lever 67 against the end of the solenoid core in which position it is locked by latch member 72 as a result of the action of the latch spring 74. Contact is then broken between contact point 68 and contact lever 40 67 and thus the pendulum contact point 62 is deenergized and no further records will be made upon record member 64. When the instrument is removed from the drill stem, record member 64 is removed, a new record member is installed and the switch contact lever 67 is reset in preparation for the next operation of the instrument.

Figure 5 is a schematic showing of the present invention employed to initiate means for photographing a floating compass element such as is disclosed in the previously mentioned Young application. There is shown at 40 the contact elements of the present invention. Lead wire 27 is connected through conductor 87 to a battery 90 the other side of which is grounded to a common ground 80. The conductor 87 is connected between the battery 90 and brush contact 83 which bears upon the surface of the drum contactor 92. The lead wire 86 from the centrifugal switch is connected to brush contact 82 bearing on the drum 92.

The motor 94 is connected through lead wire 85 to contact brush 81 and the motor is connected to the common ground 80 through lead wire 96. Also bearing on the contact drum is brush member 84 which is connected through lead wire 88, lamp 97, conductor 98 and lamp 99 to the common ground 80.

The motor 94 acts through shaft 102, spur gears 104 and 108, shaft 110, worm gears 112 to drive the drum 92. Mounted on the drum 92 is a conventional geneva drive guide cam 114 and drive pin 116 which engages the geneva gear member 118. Mounted on the face of the geneva member 118 is the pulley 119 mounting

the belt 120. The belt 120 passes over the pulley 121 which is rigidly fixed to film spool 122.

The film 124 is carried by spools 122, 123, 125 and 126 and passes through film guide 128.

There is suitably disposed at 130 a lens which is located to properly focus the light originating from the lamps 98 and 99 and reflected from compass element 131 upon the film 124 contained within the film guide 128.

The compass element generally shown at 131 comprises glass members 132 and 134 ground to provide an accurate spherical opening 136 in which is located a liquid 138 supporting a float which comprises a body 140 of transparent plastic material. Secured to the body 140 by cement is a second plastic member 142 in the form of a disc provided with a seat for a permanent magnet 144 which is in the form of a ring permanently magnetized and cemented to the member 142. A cap member 146 is cemented to the member 142 and provides a closure for the air space which provides the necessary buoyance. The surface 148 of member 142 carries engraved markings which may consist of a radial line at its periphery for the indication of azimuth and concentric circles for the measurement of inclination. On the lower surface of the member 142 there may be engraved a cross or other marking 150 serving when read against the concentric circles to indicate the degree of inclination. The cap 146 may be provided on its interior surface with a white coating to form a definite background for the photographing of black engraved markings. Alternately, the markings may be engraved in white in which case the cap may be coated to provide a black background.

There is shown in Figure 6 the development of the surface of the contact drum 92. Bearing thereon are the previously mentioned contact brushes 81, 82, 83 and 84. When the motor 94 is causing the drum to rotate the drum surface proceeds past the brushes in the direction shown by the arrow 160. The surface of the drum is divided into the conductive area 162 and non-conductive area 163. The position of the brushes shown at Figure 6 is that existing when the motor 94 is inoperative, the centrifugal switch member 40 is in an open position and the drum contactor is in position to begin a sequence of operation. The operation of the entire instrument can now be reviewed as follows:

When it is desired to operate the recording instrument the drill stem is rotated at a pre-determined speed which is known to be sufficient to cause the pendulums of the centrifugal switch element to fly outwardly and establish contact through the switch as has been hereinbefore reviewed.

When the centrifugal contact switch 40 is rotated contact is established through the centrifugal switch member and conductors 21 and 86 between the battery 90 and the brush 82. The brush 82 is bearing on the conductive surface of the drum. Also bearing on the conductive surface of the drum is brush 81 which is connected to the motor 94. Thus, as soon as contact is established through the centrifugal switch the motor will operate and cause the drum 92 to rotate.

The drill stem must be rotated to maintain contact through the centrifugal switch during time interval (a) until the drum 92 has rotated sufficiently to bring the conductive surface 162 to brush member 83 which is connected to conductor 87 directly to the battery 90. At this time

rotation of the drill stem is arrested, the motor proceeds to drive the drum, and during the time interval (b) the pin 116 engages the Geneva drive and draws the film from the spool 123 through the film holder 128 and on to spool 122 thereby presenting an unexposed portion of film within the film holder 128 in anticipation of the new photograph which is to be made. At the completion of time interval (c) brush 84 is brought to bear upon the conductive surface of the drum causing the lamps 97 and 99 to be illuminated for the period of time (d) during which the position of the compass element is photographed. At the expiration of time interval (d) the brush member 84 passes from the conductive surface to the non-conductive surface and the lamps are extinguished. At the completion of time interval (e) the contact brush 83, which is connected through conductor 87 to the battery 90, passes from the conductive surface to the non-conductive surface of the drum thereby deenergizing the conductor 85 and the motor 94. Thus the rotation of the drum ceases.

It will be observed that time interval (a) during which the drill stem is rotated is relatively short compared to the time interval (c). Thus, ample time is provided for the drill stem and the compass member to come to rest and all parts to be stationary before the photographic record is made.

After the completion of a cycle of operation, the drill stem can be raised any desired extent by the removal of sections at the surface of the ground and, when the instrument is thus raised to a new location in the drill hole at which recordings are to be made, the drill stem is again rotated and the instrument passes through a new sequence of operation. Thus numerous records can be made at various levels in the drill hole without imposing on the drill crew a fixed time schedule presenting intervals during which they must position the drill stem for the next recording and between which they may not rock the instrument without destroying the recording. When employing the present invention the unavoidable delays which may occur at the surface of the ground preventing a drill crew from maintaining such a fixed time schedule do not interfere with the making of the records nor do they jeopardize those records already made. By use of the present invention the instrument will operate only when such operation is initiated by rotation of the drill stem by the drill crew.

Figures 7 and 8 show a modification of the invention in which the pendulums, and the pendulum mountings in the upper portion of the sleeve 4, are identical with those described in connection with Figure 1. However, the contact arrangement mounted in the insulating member 22 in the lower portion of the sleeve is modified. The contact bars 202 and 204, mounted in the insulating member 22, are located in positions so as not to be contacted by the lower ends of the pendulums 18. Twisted around and soldered to each of the bars 202 is one end of each of the conductive spring wires 206. The other end of each of the wires 206, as a result of its own spring action, makes a positive contact with the bar 204.

The pendulums when moving outwardly in response to centrifugal force, as has been hereinbefore described, will bear against the contact wires 206 deflecting the wires and breaking the contacts between the wires 206 and the bars 204. The bars 202 and 204 project downwardly through

the insulating member 22. As diagrammed in Figure 8 the lead wire 208 is connected to each of the lower ends of the bars 202 and the lead wire 210 is connected to each of the lower ends of the bars 204. It will be evident that inclination, vibration or impact may cause one or possibly two of the pendulums to move outwardly and bear upon a contact wire 206 sufficiently to open the contact between the wire 206 and the bar 204. However, it can be only as a result of rotation of the switch assembly that all three of the pendulums will bear upon the contact wires and cause all three of the contacts to be open at the same time. Thus, with the three contacts connected in parallel it can only be as a result of rotation that the circuit between lead wire 208 and 210 will be broken.

This modification of the switch assembly may be employed in connection with the above mentioned Ring instrument in the circuit shown in Figure 9 in which there is generally shown at 212 the contact arrangements of the modification of the invention shown in Figures 7 and 8 with the lead wire 210 connected to the common ground wire 222 and the lead wire 208 connected through the battery 214, and through lead wire 215 to the contact 216. The contact arm 218 is connected through the solenoid coil 220 to the common ground 222.

One side of the battery 224 is connected through lead wire 228 to the contact point 230, and the contact arm 232 is connected through lead wire 234 to the common ground 222. The other side of the battery 224 is connected through the current limiting resistor 56, the pendulum member 60, the contact point 62, and an electrochemical record member 64 to the common ground 222.

When this modification of the instrument is prepared for go-devilling into the drill stem the push button 236 is manually depressed closing the contact arm 218 against contact point 216 thus initiating a current flow from the battery 214 through the lead wire 215, the contact 216, contact arm 218, armature coil 220, common ground 222, and the centrifugal switch assembly 212 back to the battery 214. The magnetic field induced by the current passing through the armature coil 220 will hold the contact arm 218 against the end of the armature and will also pull in the contact arm 232 against the other end of the armature thereby establishing contact between the contact point 230 and the contact arm 232.

The closing of contact 230 will permit a current to flow from the battery 224 through the current limiting resistor 56, the pendulum member 60, contact point 62, electrochemical record member 64, common ground 222, lead wire 234, contact arm 232, contact point 230 and the lead wire 228 back to the battery 224.

With the recording apparatus thus energized the instrument is go-devilled into a drill stem. After a succession of records have been made, as has been hereinbefore described, and it is desired to interrupt the record making process and retrieve the record element, the drill stem will be rotated at a sufficient speed to cause the pendulums to move outwardly generally simultaneously and to break the circuit between lead wires 208 and 210. Thus the current flowing from the battery 214 through the armature coil 220 will be interrupted. The field through the armature core will collapse and the tension springs 238 and 240 will open the contact arms 218 and 232 and will hold the contact arms open against vibration, inclination or impact, thus per-

manently interrupting both the current flow through the armature coil 220 and the current flow through the contact point 62 and the electrochemical record member 64 until such time as the instrument is retracted and the push button 236 is manually depressed reestablishing the current flow from the battery 214 through the armature coil 220 recreating the magnetic field in the armature core.

10 It will be evident that numerous variations, such as anchoring the pendulums at their lower ends and allowing the upper ends to respond to centrifugal force, employing various modifications of the contact arrangement, and the like, may be made in details of the embodiment of the invention without departing from the scope thereof as defined in the following claims.

What I claim and desire to protect by Letters Patent is:

20 1. A switch assembly for initiating electrical contact in a bore hole measuring apparatus comprising a chamber containing a fluid medium, floating contact means in said medium and stationary contact means in said medium, said

25 floating contact means contacting said stationary contact means in response to the centrifugal force acting on said floating contact means when the switch assembly is rotated.

2. A switch assembly for initiating electrical contact in a bore hole measuring apparatus comprising a chamber containing a fluid medium, floating contact means in said medium mounted inwardly within said chamber and stationary contact means in said medium mounted outwardly within said chamber, said floating contact means moving outwardly and contacting said stationary contact means in response to the centrifugal force acting on said floating means when the switch assembly is rotated at a rate in excess of a predetermined rate of rotation.

3. A switch assembly for initiating electrical contact in bore hole measuring apparatus comprising a chamber containing a fluid medium, a plurality of pendulum members floating in said medium, and stationary contact members mounted outwardly of one end of each of said pendulum members, the ends of each of said pendulums contacting the contact members in response to the centrifugal force acting on the pendulums when the switch assembly is rotated.

4. Apparatus for controlling the operation of a bore hole measuring instrument including an electrically operated contact means, means providing a source of electric current, and a centrifugally operated switching means, said means connected and arranged to provide a flow of current from said current source through said electrically operated contact means when said centrifugally operated switching means is made conductive as a result of rotation thereof.

5. Apparatus for controlling the operation of a bore hole measuring instrument including an electrically operated contact means, means providing a source of electric current, and a centrifugally operated switching means comprising a chamber containing a fluid and contact members floating in said fluid, said means connected and arranged to provide a flow of current from said current source through said electrically operated contact means when said centrifugally operated switching means is made conductive as a result of rotation thereof.

6. Apparatus for controlling the operation of a bore hole measuring instrument including an

electrically operated contact means, means providing a source of electric current, and a centrifugally operated switching means comprising a chamber containing a fluid, floating contact members, and stationary contact members, said means connected and arranged to provide a flow of current from said current source through said electrically operated contact means when said centrifugally operated switching means is made conductive as a result of contact being established between the floating contact member and the stationary contact members when the switch assembly is rotated.

7. A switch assembly for interrupting an electrical circuit in a bore hole measuring apparatus comprising a chamber containing a fluid medium, floating means in said medium and contact means mounted in said chamber, said floating means bearing against said contact means in response to the centrifugal force acting on said floating means when the switch assembly is rotated and opening the contact means.

8. A switch assembly for interrupting an electrical circuit in a bore hole measuring apparatus comprising a chamber containing a fluid medium, floating means in said medium mounted inwardly within said chamber and contact means mounted outwardly within said chamber, said floating means moving outwardly and bearing against said contact means in response to centrifugal force acting on said floating means when the switch assembly is rotated at a rate in excess of a predetermined rate of rotation and opening the contact means.

9. A switch assembly for interrupting an electrical circuit in a bore hole measuring apparatus comprising a chamber containing a fluid medium, a plurality of pendulum members floating in said medium mounted inwardly within said chamber and contact means mounted outwardly of each of said pendulum members within said chamber, the ends of each of said pendulums bearing against said contact means in response to the centrifugal force acting on said floating means when the switch assembly is rotated at a rate in excess of a predetermined rate of rotation and opening the contact means.

10. Apparatus for controlling the operation of a bore hole measuring instrument including an electrically operated contact means, means providing a source of electric current, and a centrifugally operated switching means comprising a chamber containing a fluid and members floating individually in said fluid, said means connected and arranged to provide a flow of current from said current source through said electrically operated contact means when said centrifugally operated switching means is at rest, and interrupting the flow of current when the switch is made non-conductive as a result of rotation thereof.

11. Apparatus for controlling the operation of a bore hole measuring instrument including an electrically operated contact means, means providing a source of electric current, and a centrifugally operated switching means comprising a chamber containing a fluid, floating members, and contact members, said means connected and arranged to provide a flow of current from said current source through said electrically operated contact means when said centrifugally operated switching means is at rest, and interrupting the flow of current when the switch is

rotated and made non-conductive by the floating members acting upon the contact members in response to centrifugal force acting upon said floating members when the switch assembly is rotated.

12. A switch assembly for controlling an electrical circuit in a bore hole measuring apparatus comprising a chamber containing a fluid medium, floating means in said medium and contact means mounted in said chamber, said floating means bearing against said contact means and effecting control of said contact means in response to the centrifugal force acting on said floating means when the switch assembly is rotated.

13. A switch assembly for controlling an electrical circuit in a bore hole measuring apparatus comprising a chamber containing a fluid medium, floating means in said medium mounted inwardly within said chamber and contact means mounted outwardly within said chamber, said floating means moving outwardly and bearing against said contact means and effecting control of said contact means in response to the centrifugal force acting on said floating means when the switch assembly is rotated.

14. A switch assembly for controlling an electrical circuit in a bore hole measuring apparatus comprising a chamber containing a fluid medium, a plurality of pendulum members floating in said medium mounted inwardly within said chamber and contact means mounted outwardly of each of said pendulum members within said chamber, the ends of each of said pendulums bearing against said contact means and effecting control of said contact means in response to the centrifugal force acting on said floating means when the switch assembly is rotated.

15. Apparatus for controlling the operation of a bore hole measuring instrument including an electrically operated contact means, means providing a source of electric current, and a centrifugally operated switching means comprising a chamber containing a fluid and members floating individually in said fluid, said means connected and arranged to control the flow of current from said current source through said electrically operated contact means when said centrifugally operated switching means is made operative as a result of rotation thereof.

16. Apparatus for controlling the operation of a bore hole measuring instrument including an electrically operated contact means, means providing a source of electric current, and a centrifugally operated switching means comprising a chamber containing a fluid, members floating individually in said fluid, and contact members, said means connected and arranged to control the flow of current from said current source through said electrically operated contact means when said centrifugally operated switching means is made operative as a result of contact being established between the floating members and the contact members when the switch assembly is rotated.
